(No Model.)

R. H. MAXSON.

STAND FOR DISPLAYING GOODS.

No. 378,206.

Patented Feb. 21, 1888.

Fig. 1.

UNITED STATES PATENT OFFICE.

RALPH H. MAXSON, OF RICHBURG, NEW YORK.

STAND FOR DISPLAYING GOODS.

SPECIFICATION forming part of Letters Patent No. 378,206, dated February 21, 1883.

Application filed December 24, 1887. Serial No. 258,938. (No model.)

To all whom it may concern:

Be it known that I, RALPH H. MAXSON, of Richburg, in the county of Allegany and State of New York, have invented a new and Improved Stand for Displaying Goods, of which the following is a full, clear, and exact description.

This invention relates to stands for displaying goods; and it consists of a stand for this purpose constructed and arranged as herein-after described and claimed.

Reference is to be had to the accompanying drawings, forming a part of this specification, in which similar figures of reference indicate corresponding parts in all the views.

Figure 1 is a perspective view of the invention ready for use. Fig. 2 is a vertical section thereof on line *x x* in Fig. 1. Fig. 3 is a detail, partly in section and broken away, 20 showing shelf-connection. Fig. 4 is a detail, partly in section and broken away, of brace-support; and Fig. 5 is a detail showing means for supporting the end of a shelf.

The stand embraces, in its general construction, a frame or open casing containing removable adjustable shelves and an adjustable and folding brace-support.

1 indicates the frame or casing formed with double inclined top 2 and bottom 2^a, sides 3, 30 and back 4, and secured to the back 4 are strips of wood 5, extending beyond the bottom 2 to form legs. To support the casing 1 a frame, 6, consisting of uprights 7 and cross-bar 8, is pivoted to strips 5, and is adjustably held in open 35 position by means of a brace-bar, 9, pivoted to a strip, 10, on the back 4, and having a spring-catch, 11, at its free end formed with shoulders 12, which engage a bent rod or loop, 13, on cross-bar 8. Any other suitable catch may be 40 used in lieu thereof.

The sides 3 are provided with an outside strip, 14, extending from top to nearly the bottom of the casing, and with short strips 15, forming grooves 16 and at intervals spaces 17.

45 Shelves 18, formed with projections 19, are mounted in the casing 1 by either sliding them in through the spaces 20 at bottom of sides 3, or inserting them at any point through the front of the casing in an inclined position end- 50 wise and sliding the projections 19 in grooves 16 until a space 17 is reached, when the shelves

18 may be slid back in a horizontal position, with the projections 19 resting on strips 15. It will be observed that there is sufficient space between the rear of the shelf and the back 4 of 55 casing to permit the shelf to be slid back, as just described. Instead of the shelves being held up in this manner, they may rest on goods, as shown in dotted lines in Fig. 2; or part of the shelves may rest on goods and the others 60 be supported by strips 15. By means of the stand herein described goods of all kinds may be easily arranged and displayed.

The stand may be mounted on a counter or in any other suitable position. It is intended 65 especially to be used with groceries, hardware, or fancy goods, and will be made of a size adapted thereto; or it may be constructed to be used for books. When not in use, the brace-support may be folded up.

Having thus described my invention, what I claim as new, and desire to secure by Letters Patent, is—

1. In a stand for displaying goods, a casing having an open front and sides formed with 75 grooves connecting at intervals with spaces, and shelves with ends having projections adapted to engage said grooves and rest on strips forming said grooves, substantially as described.

2. A stand for displaying goods, consisting of an open-front casing having sides formed with grooves connecting at intervals with spaces, and shelves with projections on their ends adapted to slide in said grooves and resting on short strips forming the grooves, and an adjustable folding pivoted brace-support, 85 substantially as described.

3. A stand for displaying goods and other articles, consisting of open-front casing 1, 90 having its sides 2, with open spaces 20 at their ends, and provided with grooves 16, extending between spaces 17, movable shelves 18, having projections 19, engaging strips 15, supporting strips or legs 5, and a folding support, 95 6, and folding brace-arm 9, having shouldered spring-catch 11, engaging loop 13 on support 6, substantially as described.

RALPH H. MAXSON.
